CLAIM

The ornamental design for a ceiling lamp as shown and described.

DESCRIPTION

FIG. 1 is a left and top side perspective view of the ceiling lamp, showing my new design;

FIG. 2 is a rear, right and bottom side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is an enlarged detail view of the portion marked 9 in FIG. 1.

The broken lines shown in the figure drawings represent portions of the ceiling lamp that form no part of the claimed design.

The alternating length broken lines in the drawings are for the purpose of showing the enlarged portion in FIGS. 1 and 9 and form no part of the claimed design.
